US0D1073758S

(12) **United States Design Patent** (10) **Patent No.:** **US D1,073,758 S**
(45) **Date of Patent:** **** May 6, 2025**

(54) **BAFFLE FOR SUBSTRATE PROCESSING SYSTEM**

(71) Applicant: **LAM RESEARCH CORPORATION**, Fremont, CA (US)

(72) Inventors: **Karthik Adappa Sathish**, Bangalore (IN); **Cody Barnett**, Beaverton, OR (US); **Mitali Mrigendra Basargi**, Karad (IN); **Ravi Kumar**, Beaverton, OR (US)

(73) Assignee: **LAM RESEARCH CORPORATION**, Fremont, CA (US)

(**) Term: **15 Years**

(21) Appl. No.: **29/856,399**

(22) Filed: **Oct. 13, 2022**

(51) **LOC (15) Cl.** **15-09**

(52) **U.S. Cl.**

USPC **D15/144**; D13/182

(57) **CLAIM**

The ornamental design for a baffle for a substrate processing system as shown and described.

DESCRIPTION

FIG. 1 is a top view of a baffle for a substrate processing system;

FIG. 2 is a bottom view of the baffle shown in FIG. 1;

FIG. 3 is a front view of the baffle shown in FIG. 1;

FIG. 4 is a back view of the baffle shown in FIG. 1;

FIG. 5 is a right-side view of the baffle shown in FIG. 1;

FIG. 6 is a left-side view of the baffle shown in FIG. 1;

FIG. 7 is a top perspective view of the baffle shown in FIG. 1; and,

FIG. 8 is a bottom perspective view of the baffle shown in FIG. 1.

1 Claim, 6 Drawing Sheets
